AIRPLANE

John T. Corrigan and Peter P. Sherry,
Walla Walla, Wash.

Application September 5, 1952, Serial No. 21,352

Term of patent 14 years

(Cl. D71—1)

To all whom it may concern:

Be it known that we, John T. Corrigan and Peter P. Sherry, citizens of the United States, residing at Walla Walla, in the county of Walla Walla and State of Washington, have invented a new, original, and ornamental Design for an Airplane, of which the following is a specification, reference being had to the accompanying drawings forming a part thereof.

Figure 1 is a top plan view of an airplane, showing our new design;

Figure 2 is a side elevation view;

Figure 3 is a bottom plan view;

Figure 4 is a front elevational view; and

Figure 5 is a rear elevational view thereof.

The dominant features of the design reside in those portions shown in full lines.

We claim:
The ornamental design for an airplane, as shown and described.

JOHN T. CORRIGAN.
PETER P. SHERRY.
